UNITED STATES PATENT OFFICE.

ELIHU LIPPITT, OF ZANESVILLE, OHIO, ASSIGNOR, BY DIRECT AND MESNE ASSIGNMENTS, TO ANNA LIPPITT, ANNA MERCER, HENRY H. STURTEVANT, AND JOHN MARTIN, ALL OF SAME PLACE.

CIRCULAR-KNITTING MACHINE.

SPECIFICATION forming part of Letters Patent No. 394,587, dated December 18, 1888.

Application filed February 17, 1888. Serial No. 264,410. (No model.)

To all whom it may concern:

Be it known that I, ELIHU LIPPITT, of Zanesville, in the county of Muskingum and State of Ohio, have invented certain Improvements 5 in Circular-Knitting Machines, of which the following is a specification.

At the present day it is a common practice to knit stockings with heels and toes therein upon knitting-machines having a single set of 10 needles arranged to reciprocate in and lengthwise of a supporting-cylinder. The heeling and toeing operations are performed by first raising the needles on one side of the cylinder beyond the reach of the operating-cams, so that 15 they remain at rest and retain their stitches, after which the cams receive an oscillating instead of a rotating motion, so as to actuate only the needles on the opposite side of the machine. During this action the operative 20 needles are raised at the end of each course, one at a time, out of action and thereafter lowered, one at a time, into action.

It is the aim of the present invention to provide a single cam which may be so adjusted 25 that it will first operate automatically to lift the needles out of action one at a time, and subsequently to lower one at a time into action—that is to say, to effect by means of a single cam the results which have heretofore 30 required the employment of two or more cams.

The essence of the invention resides in a cam adapted to swing or rock, under the influence of the needles upon two different centers, and to assume different positions in 35 consequence. Inasmuch as my improvements are applicable to existing machines without change of the same in other respects—I have illustrated in the accompanying drawings only such parts as are necessary to an understanding of the invention.

Referring to the drawings, Figure 1 is an outside face view of a portion of the usual ring employed in cylinder-machines to carry the needle-operating cams with my improved 45 cam mechanism mounted thereon. Fig. 2 is a vertical cross-section of the same on the line $x-x$. Fig. 3 is a top plan view of the same. Fig. 4 is a view similar to Fig. 1, but with the cam in its reversed position. Fig.

5 is an inside face view of the cam-ring and 50 the cams. Fig. 6 is a perspective view of the cam. Fig. 7 is a perspective view of the plate for supporting and adjusting the cam. Figs. 8, 9, 10, and 11 are diagrams illustrating the action of my cam under the various conditions encountered in practice. 55

Referring to the drawings, A represents the needle-cylinder; B, the vertical needles arranged to reciprocate in grooves in the cylinder; and C, a revolving ring encircling the cylinder, and provided on its inner face with cams which act upon the heels of the needles to effect their movements in a manner familiar to those skilled in the art. 60

The cams by which the needles receive their 65 ordinary movements in knitting may be in all respects of the usual construction. As they have no relation whatever to the present invention, it was deemed unnecessary to illustrate them in the drawings. 70

In addition to the ordinary needle-operating cams, and at any suitable point on the inside of the usual cam-ring, C, I mount the cam mechanism forming the subject of the 75 present invention.

The main cam forming the essence of the present invention is shown at D. It consists simply of a plate rounded on its upper and lower edges, and provided near opposite ends with two shoulders, d and d' , on the upper 80 side, and d^2 d^3 on the underside. These shoulders may be of the form shown in the drawings, or of any other suitable form which will adapt them to engage with the heels of the needles, to the end that the resistance offered 85 by the needles may cause the cam to rock or tip, as hereinafter explained. The cam is formed upon or fastened rigidly to a vertical arm, d^6 , having at its upper and lower ends, respectively, two horizontal pivots or journals, d^7 and d^8 . These journals are seated against and ride upon the upper and lower edges, respectively, of an intermediate plate, E, which is movable vertically in guides e , fixed to the cam-ring C, as shown in the several figures. 90

The cam-ring is provided with an opening of sufficient size to admit the cam D and per-

mit it to play vertically, this opening terminating at the top in a central seat or bearing, c , and at the bottom in a corresponding seat or bearing, c' . By raising and lowering the 5 plate E the cam may be moved vertically. When the slide is lowered, the lower pivot, d^8 , will bear in the seat c' , and the cam D will be free to swing or tip from right to left about the pivot d^8 as a center. When, however, 10 the slide is raised, the journal d^8 is lifted away from its seat and the upper journal, d^7 , seated and held, as shown in Fig. 4, in the upper bearing, c , in which position of the parts the cam can tip from right to left about the journal d^7 as a center. The plate E and the cam are urged downward by means of an arm, e' , jointed to the plate and to the frame and acted upon by a depressing-spring, e^2 . The slide and cam are lifted at the proper 20 time by means of a revolving wheel, F, mounted on the cam-ring C, and provided with a pin, f , to act against the lower end of a rigid arm, e^3 , depending from the plate E. When lifted, the slide and cam are sustained 25 by an arm, e^4 , pivoted at one end to the slide, and provided at the opposite end with an angular slot, e^6 , adapted to interlock with a stud, e^7 , on the cam-ring C. The arm e^4 is automatically disengaged, to permit the descent 30 of the slide and cam at the proper time, by means of a pivoted lever, e^8 , which is in turn actuated by the stud f on the wheel F. The wheel may be rotated in any appropriate manner, but it is usually toothed on its edge, 35 as shown, and actuated by a pawl, d^9 , pivoted to the tipping-cam D, so that as the cam rocks to and fro it will advance the wheel step by step.

The operation of the cam D is as follows: 40 Assume that it is adjusted to move upon its lower axis, d^8 , and that it is tipped to the left, as shown in Fig. 5. If, now, it be carried to the right against the needles, the heel of the first needle will encounter the shoulder d , as 45 shown in Fig. 8, and will by its resistance cause the cam to tip to the position indicated by dotted lines in said figure. In thus tipping the cam will lift the first needle to such height that its heel will be above the path of the 50 usual operating-cams, so that the needle will thereafter remain inactive. In tipping to the new position the left end of the cam rises above the level of the needle-shanks, so that all the needles after the first pass below instead of above the cam, and thus remain down 55 in their operative positions within reach of the usual operating-cams. When the motion of the cam is reversed—that is to say, when it is carried to the right, as shown in Fig. 9—its 60 right end encounters the shank of the first needle, which acts to tip the cam to the left to its original position, as shown by dotted lines, the first needle being lifted out of action and the following needles caused to pass beneath the cam and remain in action. Thus it 65 will be seen that as the cam is carried to and fro the needles at the end of the operative

line are lifted automatically one at a time out of action. After the lifting of the needles is completed, the cam is raised bodily to its upper position, so as to swing about its upper axis, d^7 .

Assume that the cam stands in its left-hand position, as shown in Fig. 10, as it moves to the left against the needles its under shoulder, d^2 , will encounter the shank of the first needle, the resistance of which will cause the cam to swing to the right, as shown in dotted lines, and in so doing carry the first needle downward to an operative position, and at the same time assume such position that the falling needles will pass over the cam and remain in their elevated or inoperative positions. On reversing the motion of the cam its shoulder d^2 will encounter the heel of the first needle, 75 whereupon the cam will be carried to the left thereby and assume its original position, (shown by dotted lines,) the needle being moved downward and the cam assuming such position that the following needles will pass 80 over without being depressed. This action of depressing the needles automatically one at a time is, it will be perceived, the reverse of the lifting action.

In Fig. 1 I have represented the cam in its 95 lower position for elevating the needles, this being the position which it occupied during the earlier part of the operation of forming a heel or toe. By means of a pawl and ratchet the wheel is turned in such manner that when 100 the proper number of needles have been lifted out of action the cam will be automatically raised and its action reversed, so that the needles will be again depressed and rendered 105 operative.

I prefer to employ in connection with my automatic cam the needle operating or knitting cams represented in Fig. 5; but it is to be understood that my invention is not restricted to such combination, and that my device is operative in connection with any other suitable arrangement of cams for moving the needles to effect the ordinary knitting action. In this figure G and G' represent two depressing-cams pivoted adjacent to and on opposite 110 sides of the cam D, their office being to lift the needles to the end of the cam D and to prevent the needles from falling accidentally below their proper levels. H and H' represent two depressing-cams arranged above the cams G and G', to prevent the needles from 115 being lifted accidentally out of position. I and I' are two small cams or switches pivoted at their inner ends above the cams H and H', and serving, when lifted, to bring the needles 120 which are elevated out of action downward in position to strike against the cam D when the latter is elevated to the proper position for depressing the needles. When these cams are used, the cam D may be made of smaller 125 size and given a shorter adjustment in a vertical direction than would otherwise be required, since the other cams serve to move the needles downward or upward, as the case 130

may be, within the path of the cam D. When the cams I and I' are employed, the lifting-springs *i* are employed to hold them in, and slides or stops of any suitable character to 5 lock them out of action.

While it is preferred to provide the cam with two distinct rigid pivots or journals, and to sustain and vertically adjust the cam by means of the slide E, bearing between said 10 journals, it will be apparent to the skilled mechanic that these details are not of the essence of the invention, and that any equivalent construction which will permit the cam and the pivotal point upon which it rocks for 15 the time being to be raised and lowered in relation to the normal path of the needle-heels, so that the forward elevated end of the cam will ride over or under the heel of the first needle, as demanded, will fall within the 20 scope of my invention.

I do not claim, broadly, in this case a rocking cam shouldered at its two ends for the purpose of automatically raising or automatically lowering the needles one at a time; nor 25 do I claim herein the combination of such rocking cam with switches or wing-cams I I', these features forming the subject-matter of a separate application filed by Hansdorfer & Lippitt on the 6th day of January, 1888, Serial 30 No. 260,016.

Having thus described my invention, what I claim is—

1. In a knitting-machine, a cam shouldered on its upper and under edges and pivoted, 35 that it may rock under the influence of the needles, in combination with means, substantially as described, for raising and lowering the cam bodily at will, whereby the operative end of the cam may be caused to override or 40 underride the heel of the first needle at will.

2. In a knitting-machine, and in combination with the usual cylinder-needle and needle-operating cams, the rocking shouldered cam D, adapted to be rocked by the needles, 45 and means, substantially as described, for fixing the cam at will above or below the normal path of the needle-heels, whereby the cam may be caused to carry the needles one at a time into or out of an operative position, as de- 50 manded.

3. In a knitting-machine, a needle-actuating cam having two journals or axes, one above the other, in combination with the slide for raising and lowering the cam, and the two seats or bearings adapted to receive the respective journals, whereby the cam may be adjusted to rock upon either of the two axes at will. 55

4. The shouldered rocking cam, as described, and its vertically-movable support, in combination with a connecting mechanism actuated by the rocking motion of the cam to raise and lower said support. 60

5. The automatic rocking cam D, as described, in combination with its rising-and-falling support, the wheel to raise and lower the support, and the wheel-actuating pawl attached to the cam, whereby the cam is caused to lift the needles out of operation and then reverse its action and return them automatically to their operative positions. 65

6. The cam D, having the shouldered ends and the two journals, in combination with the adjustable supporting-plate E, lying between said journals, the ring or frame having the 75 bearings *c c'* therein, the depressing-spring and its arm, and the sustaining-latch *e*. 70

7. In combination with the rocking cam, its two bearings and its supporting-slide, the latch-arm *e*, to sustain the slide and cam in 80 their elevated positions.

8. In a cylinder-knitting machine, the cam D, constructed to tip sidewise under the influence of the needle-heels thereunder or thereover, in combination with means, substantially as described, for fixing said cam at different heights, whereby it is adapted for raising the needles automatically out of action, one at a time, and for lowering them in like manner into action. 85

In testimony whereof I hereunto set my hand, this 11th day of January, 1888, in the presence of two attesting witnesses.

ELIHU LIPPITT.
